KNOB FOR DOORS, DRAWERS AND THE LIKE

Alfred H. Bottom, 5801 Lawnview St. NW., and Richard C. Henson, 1323 12th St. NW., both of Canton, Ohio

Filed Jan. 17, 1966, Ser. No. 632

Term of patent 14 years

(Cl. D50—3)

FIG. 1

FIG. 2

FIG. 3

FIG. 1 is a front elevational view of a knob for doors, drawers and the like embodying my new design.

FIG. 2 is a section taken along line 2—2 of FIG. 1.

FIG. 3 is a fragmentary section taken along line 3—3 of FIG. 1.

We claim:

The ornamental design for a knob for doors, drawers and the like, as shown.
